UNITED STATES PATENT OFFICE.

MONROE STEVENS, OF SHELLMAN, GEORGIA.

WATER-ELEVATOR.

SPECIFICATION forming part of Letters Patent No. 375,215, dated December 20, 1887.

Application filed October 25, 1886. Serial No. 217,150. (No model.)

To all whom it may concern:

Be it known that I, MONROE STEVENS, of Shellman, in the county of Randolph and State of Georgia, have invented a new and Improved 5 Water-Elevator, of which the following is a full, clear, and exact description.

My invention relates to an apparatus for elevating water especially adapted for use with wells, and has for its object to so elevate the 10 water in a proper bucket as that when the said bucket has reached its highest point it will be automatically engaged by a hinged chute, and the water automatically emptied through the 15 bottom of said bucket into said chute, the entire operation being quickly and easily carried out through the medium of an ordinary windlass.

The invention consists in the construction and combination of the several parts, as will 20 be hereinafter fully set forth, and pointed out in the claims.

Reference is to be had to the accompanying drawings, forming a part of this specification, in which similar figures of reference indicate 25 corresponding parts in all the figures.

Figure 1 is a side elevation, partly sectional, of my water-elevator, with the bucket in the well. Fig. 2 is a central vertical section of the same. Fig. 3 is a horizontal section through 30 line yy of Fig. 2, illustrating the bucket and chute elevated to discharge the water; and Fig. 4 is a perspective view of the valve used in connection with the well-bucket.

In the construction of my water-elevator the 35 well 1 may be provided with a curb, 2, side bar, 3, and an ordinary tower, 4, having a pulley, 5, pivoted in the top bar thereof. At the rear of the tower 4, within the projecting arms of the side bars, 3, a drum, 6, may be pivoted, operated, 40 preferably, by a crank in connection with a ratchet and pawl. Upon the outer face of one of the side bars, 3, I usually pivot a hand-lever, 7, which may be such as shown in the drawings, purposed to engage at one end the 45 shaft of said drum, to control the rapid descent of the bucket 8, which is connected thereto by a rope, adapted to pass over the pulley 5, above mentioned.

To the rear upright of the tower 4 I attach 50 a transverse beam, 9, and hinge thereto a bar, 10, provided with a central slot, 11, and a swivel-hook, 12, at its free end. A distance

below the said transverse bar 9 I attach to the opposite or front uprights of the tower a transverse supporting-bar, 13, which bar is adapted 55 to receive and sustain the end of the said hinged slotted bar 10, when the bucket is in the well, as will be hereinafter more fully set forth. Beneath this hinged slotted bar 10, to the rear of its slot 11, I hinge a guide-bar, 14, 60 provided with a slot, 15, extending nearly to its forward end, and friction-rollers 16, attached to the upper face thereof. Through the central slot, 11, of the hinged bar 10, and also through the slot 15 of the hinged guide-bar 14, the rope carrying the bucket 8 is made 65 to pass in a direct line from the pulley 5, the said rope being fitted with a button, 17, over its connection with the bail of said bucket.

To the inner side of the well-curb at the top 70 centrally its front portion I hinge a chute, 18, from the under side thereof at such a point near the center as that it will turn inward of its own weight parallel with the said curb, yet need but slight exertion to raise the said 75 chute to an inclined horizontal position over the curb. I now connect the chute 18 with the swivel-hook 12 of the hinged slotted bar 10 by means of a chain, 19, attached to said chute near its pivotal point, the said chain 80 being of a length as much greater than the distance from its point of attachment to the chute when in a vertical position and the end of said swivel-hook 12, when the slotted bar 10 rests upon its supporting-bar 13, as may be required 85 to obtain a proper inclination of the chute when raised horizontally. The bottom of the bucket 8 is made with a central aperture, 20, having hinged thereto a valve, 21, covering said aperture, the said valve being provided 90 with four openings, 22, therein located, preferably one at each corner of a rectangle formed on said valve, and a rectangular groove, 23, upon the under side thereof, connecting with said openings 22. The entire lower face of the 95 valve is adapted to receive a covering, 24, of an elastic material—such as rubber or thin leather—through which covering a pin, 25, attached centrally to said valve, projects, the said pin 25 being of a length sufficient to allow 100 the same to extend through and beyond the central aperture, 20, in the bottom of said bucket.

The object of constructing the valve with

the openings and grooves is to permit the water to press directly upon the elastic covering and hold it firmly on the bottom of the bucket. They also permit the elastic material to be held on the bottom of the bucket with sufficient pressure to prevent leakage should a pebble or other obstruction get under the valve.

In operation, when the bucket is in the well, as shown in Fig. 1, it is elevated by means of a windlass in the usual manner. When the button 17, above the bail of the bucket, comes in contact with the end of the hinged guide-bar 14, it raises the same, which, as it is pressed upward, carries the bucket through its contact with the rope supporting the same as it ascends over toward the front of the curb, where the chute 18 is pivoted. In the further process of ascension, as the button 17 causes the guide-bar to assume a horizontal position and engage the hinged slotted bar 10, the said bar is also carried upward. At this point the bucket is no longer guided forward, as the rope now engaging the rear end of the slot 15 of the guide-bar 14, which is in position parallel with the front end of slot 11 of the hinged bar 10, has but limited play between the two. As the two hinged bars are carried together still farther upward, the chain 19 is tightened and the chute elevated under and in line with the bottom of the bucket, following the same up until, by the tightening of the connecting-chain, the chute is brought to its proper inclined horizontal position, (shown in dotted lines in Fig. 1 and in positive lines Fig. 3,) whereupon the bucket 8 rests upon the face of the said chute, near the rear, and as the pin 25 of the bucket 8 strikes the face of the chute the valve 21 in the bottom of said bucket is

raised and the contents automatically emptied 40 therefrom into the chute through the central aperture, 20. When the bucket is sent down again, the chute takes a vertical position in advance of the descent of the bucket.

Having thus fully described my invention, 45 I claim as new and desire to secure by Letters Patent—

1. In a water-elevator, the combination, with a well-bucket and its operating-rope, of a pivoted chute or trough, a slotted hinged bar, 10, 50 connected to said chute or trough, and a slotted guide-bar, 14, hinged to the under side of the bar 10 at the rear of the slot therein, substantially as herein shown and described.

2. In a water-elevator, the combination, with a well-curbing, a tower above the same, and a well-bucket and its operating-rope, of the chute or trough 18, hinged to the curbing, the bar 10, provided with the slot 11 and hinged to the tower, the chain 19, connected to the free end 50 of the bar 10 and to the chute or trough, and the guide-bar 14, provided with the slot 15 and the friction-rollers 16 and hinged to the under side of the bar 10 at the rear of its slot, substantially as herein shown and described. 65

3. In a water-elevator, a bucket provided with an aperture, 20, in its bottom, and a valve, 21, hinged over said aperture, the said valve having a central projecting pin, 25, apertures 22, a rectangular groove, 23, in its under side, 70 and a flexible bottom covering, 24, substantially as shown and described, and for the purpose herein set forth.

MONROE STEVENS.
